EDWARD C. LEWIS, OF BENTON HARBOR, MICHIGAN.

Letters Patent No. 97,782, dated December 14, 1869.

IMPROVED WINE AND CIDER-MILL.

The Schedule referred to in these Letters Patent and making part of the same.

I, EDWARD C. LEWIS, of Benton Harbor, in the county of Berrien, and State of Michigan, have invented a new and useful Combined Wine and Cider-Mill.

Nature and Objects of the Invention.

My invention relates to that class of fruit-grinding mills adapted, by conversion, to grinding or crushing, to the proper extent, either apples, and similar fruits, (for cider, &c.,) or grapes, and similar fruit, (for wine, &c.,) and

My invention consists in the employment, in connection with suitably-arranged grinding or crushing devices, of a novel and simple combination and arrangement of removable and adjustable guides and guards, and devices for supporting the same, by which to make said conversion.

Description of Drawings.

In the accompanying drawing—

Figure 1 represents a perspective view of my combined mill, adjusted for grinding apples for cider.

Figure 2, a vertical transverse section of the same, as represented in fig. 1.

Figure 3, a vertical transverse section, in a plane parallel to that of fig. 2, of the same, adjusted for grinding or crushing grapes for wine.

Similar letters of reference indicate like parts in the several figures.

General Description.

In the drawing—

A represents the frame of the mill;

B B, C C, the crushing-rolls;

B' C', the shafts of the rolls B C;

D, the main, and E, a supplementary driving-shaft;

E E' E' E'', the gearing employed to connect the several shafts;

F, a pulley, provided on the supplementary driving-shaft D', for the application of motion to the rolls from some motor, through a belt; and

G G, angular heads, provided on the driving-shafts D D', for the application of winches or cranks thereto, by which to operate the rolls.

H represents a fly-wheel, provided on the driving-shaft D.

a* a* represent closed ends of the frame A.

I represents the hopper;

J, the regulating-slide of the same;

i i, cleats, forming the supports and guides of the slide J;

K, a clamp-screw, for holding the slide J at its different adjustments;

k, a nut, for the engagement of the screw K;

k', a washer, placed beneath the head of the screw; and

j, a longitudinal slot in the slide, for the reception of the screw.

L represents a fixed board or plate, forming the back of the intermediate chamber of the mill, between the two sets of rolls, and the sides of which are formed by the ends a* of the frame; and

L', a corresponding board or plate, forming the front wall of said chamber, and adjustable, so as in one position, (fig. 2,) in conjunction with L, to guide the partially-crushed fruit from the upper to the lower set of rolls, (for cider, &c.,) or by adjustment to another position, (fig. 3,) to admit of the introduction of a cutoff, to carry off the fruit as it comes from the first set of rolls, (for wine, &c.,) and to form a guard to secure the proper discharge of the same.

M M' represent rods for the support of the walls L L' of the intermediate chamber of the mill, being respectively fixed and adjustable.

m m' represent the sockets for the rod M, occupied, respectively, in supporting the wall L' in its two positions.

l represents the pivots or hinge of the wall L', and l', a staple on the same, for the reception of the rod M', when in its socket m'.

a a' represent cleats, on the inner sides of the ends a* of the mill, serving to close the crevices between the walls L L' and the ends, when the former serve to close the intermediate chamber of the mill, to cause the fruit to pass through the second set of rolls, and to form abutments, against which to support said walls in this position.

N O represent the chutes for carrying off the crushed fruit and juice, being respectively supported, when in use, in a proper inclined position below both, and below the upper, only, of the sets of rolls for this purpose.

a² a² represent cleats, provided on the ends of the mill, beneath the second set of rolls, for the support of the chute N, and a³ a³, notches or grooves in the cleats a a', for the support of O.

P P represent scrapers, for cleaning the rolls C.

The materials employed in building the mill, and the precise form of its several parts, their proportions and precise arrangement, are capable of variation.

The frame A, with the hopper I J, the walls L L', of the intermediate chamber of the mill, and the discharge-chutes N O, are preferably made of wood, the remaining parts of iron, or other suitable metal.

The rolls B C are preferably, respectively, toothed and plain, and cast hollow, as represented; but one of the first set (B) may preferably be employed in connection with a toothed concave.

The shafts B' C', D D', are mounted in suitable boxes in the frame, as shown.

The shaft D', with its appurtenances, may be dispensed with, the shaft D being provided with a pulley,

if requisite. When both are employed, either or both may be provided with the angular heads G G'. D' when employed as shown, is preferably made removable, so as to be removed when not in use, to save the power which would otherwise be consumed in driving it.

The inner one of the gears F³, of the rolls C, may preferably be made removable, to prevent the operation of said rolls when they are not used.

Any suitable means, other than those shown and described, may be employed to support the wall L, of the intermediate chamber, if preferred; and any equivalent of the means l l', M', m', for supporting the adjustable wall L', may be used.

The discharge-chute N (one) may be removable, and serve in both uses of the mill, being supported respectively on the cleats in the groove a³, the supplementary chute O, for secondary use, be dispensed with, or both be employed, as preferred. In either case, any suitable means may be employed for the support of the said chute or chutes.

The scrapers P, for the rolls C, may be supported and arranged in any suitable manner, similarly or diversely. As shown, they are attached, respectively, one to the inner side of a cross-bar, connecting the two bars of the frame in which the rolls C are journaled, and to the upper side of the chute N, projecting, respectively, down and up, in conformity with their position, to secure the discharge of the matter removed.

Operation.

The operation of the mill is as follows:

For cider: The slide J being properly adjusted and secured by the clamp-screw K, the rolls B and C both in gear, the wall L' of the intermediate chamber of the mill closed, (against its supporting-cleat a') and supported by the rod M', in its socket m, and the chute N in place, under the rolls C, as represented in figs. 1 and 2, the apples are placed in the hopper I, and motion imparted to the rolls through one or both of

the driving-shafts D D', and their connecting-gearing, E E¹ E² E³; the apples being carried down by the teeth of the exposed one of the rolls B, and crushed and torn between them, thence passing through the intermediate chamber to the rolls C, where the crushing-operation is completed, and they reduced to pomace, which, with the expressed juice, is discharged over the chute N into receptacles placed to receive it.

For wine: The adjustment of the feed-regulating slide J being attended to as before, the wall L' of the intermediate chamber, supported in its open position by the rod M', in its socket m', passing through the staples l' on it, and the chute O, (or N,) supported in the groove a³, between the rolls B and C, as represented in fig. 3, and, if desired, the rolls C disconnected from B, the grapes or other fruit are placed in the hopper, and, motion being imparted, fed and crushed between the rolls B, and then discharged by the chute, without passing through the rolls C, the wall L' serving, in this adjustment, as a guard to prevent the pulp and juice flying out of the mill.

Claims.

I claim, as new—

1. The door or adjustable wall L', of the intermediate chamber between the two sets of grinding or crushing-devices, as and for the purpose set forth.

2. The combination of the chute-supports a² a³, arranged, relatively to the two sets of grinding or crushing-devices, as shown, and the adjustable wall L', and removable chute or chutes N O, as and for the purposes described.

To the above specification of my wine and cider-mill, I have signed my hand, this 18th day of August, 1869.

EDWARD C. LEWIS.
